UNITED STATES PATENT OFFICE.

EDWARD N. DICKERSON, OF NEW YORK, N. Y.

ACETYLENE-GAS BURNER.

SPECIFICATION forming part of Letters Patent No. 678,550, dated July 16, 1901.

Application filed January 22, 1897. Serial No. 620,214. (No model.)

To all whom it may concern.

Be it known that I, EDWARD N. DICKERSON, of No. 253 Broadway, in the city, county, and State of New York, have invented a new and 5 useful Improvement in Acetylene-Gas Burners, of which the following is a full, true, and exact description, reference being had to the accompanying drawings.

A difficulty in burning acetylene gas has 10 been found due to the fact there is a tendency of the gas to break up and deposit its carbon at the orifice where the gas issues to the air for the purpose of burning. Many efforts have been made to produce a burner 15 which will not clog under these conditions. It has been discovered that a lateral indraft of air at about the orifice will cut off the flame from the burner-orifice. Such draft has been produced by an independent air- 20 pump and requires a separate pipe and is consequently not always applicable. I have discovered that practically the same result may be obtained by a peculiarly-shaped burner in which the orifice is located in a 25 cavity so shaped that the air is drawn down and against the flame, tending to prevent the combustion immediately at the orifice and causing the carbon-depositing temperature to exist only at a distance above the orifice. 30 It is believed that the deposition of the carbon occurs only at an intermediate temperature between the normal temperature of the gas and the point to which it may be heated by its combustion. The principle of my in- 35 vention consists, therefore, in supplying the gas with a limited amount of oxygen at its point of escape from the orifice, which oxygen or air is caused to flow substantially at right angles to the delivery-orifice. By unit- 40 ing two of these orifices the ordinary union-jet flame is obtained.

My invention will be readily understood from the accompanying drawings, in which—

Figure 1 represents a section of my preferred form of burner; Fig. 2, a section of a modified form and Fig. 3 two of the burners of Fig. 1 mounted so as to make a flat flame.

A represents the burner-tip, of any suitable 50 material. I have found metal to give good results. It may be mounted upon any suit-

able support B. It is provided with a single orifice C, and the gas jetting upward in the burner, Fig. 1, draws in a current of air around the sides of the basin D, which is 55 turned at right angles by the lower inclined sides. This inrush of cold air being so caused to flow into the gas at its point of escape has a tendency to prevent the gas reaching its kindling temperature immediately at the de- 60 livery. Consequently in actual practice the deposit of carbon is hindered. In Fig. 2 substantially the same view is shown, excepting that the gas is delivered slightly above the bottom of the basin D through the orifice E, 65 as shown.

In Fig. 3 a union-jet arrangement is shown. This figure is of course merely by way of illustration, for the arrangement can be mounted in many different ways.

It will be observed also that the downwardly-moving air is in part impoverished of its oxygen by the flame, which fact may have some influence on the question of the carbon deposit. Of course the theories here adduced 75 are not stated as necessarily correct, but only as explanatory. It is desirable, in order to secure good results, that the cavity should have a definite relation to the gas-pressure, in order to secure the impoverishment of the 80 air. I have found that a cavity one-quarter of an inch in diameter and one-quarter of an inch deep, having a gas-pressure of approximately five inches, works well. I do not state these proportions as essential, but as desir- 85 able.

What I claim as my invention, and desire to secure by Letters Patent, is—

A burner for acetylene gas having a central cylindrical orifice located in the bottom 90 of an opening substantially hemispherical in shape and having a slight elevation in the bottom of the opening through which elevation passes the orifice, substantially as described.

In testimony whereof I have signed my name to this specification in the presence of two subscribing witnesses.

E. N. DICKERSON.
